Primary Examiner — Jasmine Mlinarcik*Assistant Examiner* — James P McKane(57) **CLAIM**

The ornamental design for trousers, as shown and described.

DESCRIPTION

FIG. 1 is a rear, top perspective view of trousers, showing my new design;

FIG. 2 is a left side elevation view thereof; and,

FIG. 3 is an enlarged view of detail "3" identified in FIG. 1. The dash-dot-dot-dash broken lines in the figures illustrate portions of the trousers that form no part of the claimed design. The dash-dot-dot-dash broken lines in FIGS. 1 and 3 are for the purpose of illustrating the enlarged view indicators and form no part of the claimed design. The evenly spaced dash lines are used to illustrate the stitching and form a part of the claimed design.
